(57) **CLAIM**

The ornamental design for diagonally hinged container, as shown and described.

DESCRIPTION

FIG. 1 is top isometric view of a diagonally hinged container, showing our new design in an open position.

FIG. 2 is a view similar to FIG. 1, in a closed position.

FIG. 3 is a top view thereof in a closed position.

FIG. 4 is a bottom view thereof in a closed position.

FIG. 5 is a front elevation view thereof in a closed position.

FIG. 6 is a right side elevation view thereof in a closed position, the left side elevation view in a closed position being identical thereof; and,

FIG. 7 is a rear elevation view thereof in a closed position.
